UNIVERSAL INDICATOR CLAMP

Warren H. Larson, Minneapolis, Minn.

Application October 4, 1944, Serial No. 557,207

2 Claims. (Cl. 248—226)

This invention relates to improvements in clamps for holding the dial test indicators used in precision machining and tool making in machine shops.

The ordinary clamp for this purpose comprises a clamp having a single tapped opening in its head to receive the threaded end of a bar or post upon which the conventional dial indicator is clamped or supported, said post extending coaxially with respect to the clamp spindle or screw. The use of a clamp of this kind is limited, however, to situations wherein it may be secured to some adjacent part of the machine with its single post extended into proximity to the work to properly support the indicator with respect thereto, and in many instances it will be found either that space does not permit the proper positioning of the clamp, or that when the clamp is located in a suitable place the post cannot be disposed adjacent the work at all. Then too, and this is important, in much work several tests must be applied to the work and these must now be carried out in succession or one at a time with the single post type of clamp, greatly increasing the total time for testing and setting up the work.

Having in mind these facts it is the primary object of my invention to provide a universal clamp for this purpose whereon a plurality of indicator supporting posts may be arranged at spaced and angularly related positions with respect to each other and set up in any combinations suitable to the work. Thus the clamp itself may be secured to the machine, or any supporting part convenient to the purpose, and a post attached to the clamp at an angle and position such as, in the majority of cases, to bring the indicator mounted thereon to operative position with respect to the work. A further object is to provide a multiple post clamp whereon two, or even more, posts may be arranged to support any number of separate indicators required for simultaneously testing and indicating the trueness of different surfaces of the work. Thus the work may be trued up in one operation, so to speak, with a considerable reduction in the setting up time for each piece.

These and other more detailed and specific objects will be disclosed in the course of the following specification, reference being had to the accompanying drawing, in which—

Fig. 1 is a fragmentary plan view of a lathe and a work piece mounted therein and illustrating the simultaneous checking of the end and peripheral surfaces of the work by two separate dial in-

dicators supported by two posts in my universal clamp.

Fig. 2 is an enlarged side elevation of the clamp and two posts associated therewith.

Fig. 3 is a plan or head view of the clamp alone.

Fig. 4 is a fragmentary sectional view along the line 4—4 in Fig. 2.

Referring now more particularly and by reference characters to the drawing my improved clamp is indicated generally at 5 and comprises a substantially C-shaped frame 6 having an upper arm 7, and lower arm 8 connected by a back member 9, all suitably ribbed for strength as clearly shown. Formed at the end of the upper arm 7 is a head 10 and at the corresponding end of the lower arm 8 is an integral tapped sleeve 11 through which is threaded a spindle or clamp screw 12. A knurled head 13 on the lower end of the spindle permits it to be adjusted toward or away from the head 10 so that the clamp may be secured in a conventional manner to any part of a machine or other body disposed between the upper end of the spindle and lower face of the head. Said upper end of the spindle is provided with the usual rotatable cap 14 and the underside of the head 10 with a shallow V-shaped notch 15 for convenience in rigidly and properly gripping the support, whatever it may be.

In the ordinary clamp as supplied the tool maker or machinist for this purpose at present, the head 10 is provided with a single tapped socket or opening in the location here designated at 16, to receive the threaded, reduced end 17 of an indicator mounting post or bar 18 which, when screwed with said socket, obviously extends straight from the clamp in substantially axial alignment with the spindle 12.

In accordance with my invention I provide any number of additional posts 18, as indicated in the drawing, and for their selective reception provide the clamp head 10, in addition to the one socket 16 in its upper side, with three similar tapped sockets 19, 20 and 21 disposed each substantially at right angles to the other and located respectively in the front 22, and sides 23—24 of the head which as clearly shown is square in shape to provide the necessary surfaces for this purpose. To provide a base or shoulder against which the posts may be tightly screwed the outer ends of the sockets 16, 19, 20 and 21 open through surrounding, faced-off generally circular bosses indicated at 25.

Referring now more specifically to Fig. 1, I illustrate therein a situation in which my improved clamp is of great advantage. Here the

work A, chucked in the chuck B of a lathe C for example, is circular in shape and has a peripheral surface D and flat end surface E. For proper machining it is assumed that the peripheral surface D must run true about the axis of rotation of the lathe chuck while the end surface E must be run true in a plane at right angles with that axis.

In the previous practice it would be necessary to first check either surface D or E of the work by first adjusting the clamp and indicator thereto, and after trueing that surface, to shift the clamp and indicator to another position suitable for checking the last surface. This would not only require a considerable time and duplication of efforts but might easily result in repeated tests being required after each adjustment of the work in the chuck, as will be readily apparent.

In the use of my improved clamp, however, I may, as indicated, secure it to the lathe at any appropriate point and in the instance illustrated affix two separate posts, designated at 18^a and 18^b, at right angles to each other and extending respectively toward the peripheral and end surface D and E of the work A. In the particular mounting shown the posts 18^a and 18^b are, respectively, screwed into the sockets 20 and 19 in the head 10 of the clamp. By means of the conventional fixtures and clamps F provided for this purpose I then may support separate dial test indicators G1 and G2 on the posts 18^a and 18^b so that their work-contacting points properly ride the surfaces D and E of the work as shown to simultaneously indicate any deviations on these surfaces from true, and indicate the effectiveness of the connections as they are made. Thus I secure a great saving of time in setting up each piece as will be clearly evident.

My clamp is not, of course, limited to use of

two posts and indicators, and any number may be employed, and the posts disposed in any of the sockets in the clamp as may be required for each individual job. In addition the wide choice of angles of a single post with respect to the clamp, makes it possible to meet the requirements in many set-ups where the single post, extended straight from the clamp as hereinbefore set forth, would not be useful at all, due to crowded conditions, intervening obstructions between the work and only available clamp position, and other factors. Further advantages of my clamp will be readily appreciated to those skilled in the art without further description herein.

It is understood that suitable modifications may be made in the structures disclosed, provided that such modifications lie within the spirit and scope of the appended claims. Having now, therefore, fully disclosed my invention, what I claim to be new and desire to secure by Letters Patent is:

1. A device of the character described for supporting a plurality of dial test indicators in positions for simultaneously taking readings from separate surfaces of the work being tested and including posts for carrying the indicators, comprising a clamp member including a head having a plurality of angularly positioned sockets adapted to selectively receive and support the posts in position for properly presenting the indicators thereon to the work, the said sockets being all disposed at right angles to each other.

2. A clamp for selectively supporting one or more dial indicator mounting posts, comprising a clamp frame having a square head portion, and said head portion having post receiving sockets opening through at least four surfaces at right angles to each other.

WARREN H. LARSON.
